UNITED STATES PATENT OFFICE.

GEORGE STORM, OF NEW YORK, N. Y.

ART OF TREATING TOBACCO.

SPECIFICATION forming part of Letters Patent No. 337,457, dated March 9, 1885.

Application filed December 2, 1885. Serial No. 184,511. (No specimens.)

To all whom it may concern:

Be it known that I, GEORGE STORM, of the city of New York, in the county and State of New York, have discovered and invented certain new and useful Improvements in the Art 5 of Treating Tobacco, for which I made application for Letters Patent August 17, 1885, Serial No. 174,554, of which the following is a divisional specification.

Before tobacco is manufactured it usually undergoes a fermentation, which, in the first instance, is generally caused by the humidity and warmth of the atmosphere acting upon the natural elements of the tobacco, and this 10 is termed "sweating." In addition to this first sweat the tobacco, before it can be used for certain purposes, is moistened, or "cased," as it is termed, and subjected to an artificial heat, which causes it to again ferment, and this 15 fermentation is known as "resweating." The sweating and resweating deprives the tobacco of part of its gum or juice, and produces different colors from what appeared upon the curing or drying of the tobacco after being cut 20 and taken from the plantations. The natural sweat or fermentation has heretofore been practically uncontrollable, and consequently very uneven colors are produced by it, some portions of the leaf being dark while others are 25 light, besides which it weakens the texture during the period necessary for aging; and if very bright colors are desired, as is frequently the case, particularly where it is to be manufactured into smoking-tobacco, the sweat or 30 natural fermentation is liable to continue until the tobacco either becomes too dark or too mottled to be used for purposes for which it would otherwise have been well adapted. The natural sweat also leaves the tobacco in a condition, as to color and appearance, which often-times unfits it for use in the manufacture of 35 cigars, and to overcome these effects by producing even or uniform colors, as well as to further eliminate or neutralize its rank elements, the tobacco is generally subjected to 40 the resweating process before being worked up. In the resweating process fermentation is induced and kept up for a certain length of 45 time, according to what are deemed to be the requirements of the tobacco with reference to 50 the uses to which it is to be put. In determining the length of time during which this

fermentation should be continued one of the most important factors to be taken into consideration is the shade or color which it is desired to produce, and this is especially true where light or medium colors are wanted. In order to bring the tobacco to the desired shade and to keep it from becoming too dark, the operator has to examine it while it is under treatment, because no certain length of time at fixed temperatures can be depended upon, inasmuch as different lots or vegas of tobacco put into fermentation under precisely the same conditions would be very differently affected by it, 60 owing to the difference in their texture or constituent elements, caused, partially at least, by the climatic influence exercised upon the tobacco during its growth. The judgment of the operator must therefore be taken as the 65 criterion as to when fermentation should cease; but his judgment is dependent upon the appearance of the tobacco when examined by him, and what then seems to him to be its empyreumatic properties or odors, as well 70 as the condition of its texture. If the tobacco appears to be sufficiently fermented, it is taken from under the direct influence 75 of the artificial heat, which during the process of resweating is made to act upon it, and satisfactory results might be obtained in most instances by this method of treatment if the tobacco could be worked up at once, or if 80 other influences did not continue to affect it. It is not always practicable, however, to manufacture the tobacco as soon as it is taken from the resweating process, and more frequently than otherwise it remains for a considerable 85 length of time in packages or piles of some magnitude, and while in this condition the 90 fermentation already induced continues to such an extent as to affect the tobacco to a very uncertain degree, because this after fermentation has heretofore been quite as uncontrollable as the natural sweat. Whether the tobacco has 95 been under the resweating process or not, the rooms in which it is stored have, from mistaken ideas, generally been kept warm or moderately so during the whole year, the temperature, however, being susceptible to the influences occasioned by changes of the weather; and the warmth of the rooms, together with the humidity of the atmosphere at times, act 100 upon the inherent elements of the tobacco,

which give it a natural propensity to ferment when in a moist condition and placed in bulk or sufficiently large packages, thus causing fermentation or sweat. If the tobacco has been 5 previously resweated and is but a short time from the process, the fermentation continues, and this after fermentation is kept up partially by the condition of the store-rooms and partially by the heat from the resweating process 10 which it still retains. The effects of such fermentation and the continuance of the resweating fermentation occasion injuries to the tobacco, because fermentation, aside from evaporating a portion of the gum or juice of the 15 tobacco, brings it to the surface and loosens it to such an extent that it is inclined to flow or work its way to the veins, which, acting as conduits, lead it to the stem through or along which it either runs off or is absorbed; and 20 the hitherto uncontrollable fermentation, whether induced from natural causes or forming a continuance of the resweating process, keeps depriving the tobacco of its gum, and of course weakening its texture. Moreover, 25 it is necessary that a certain percentage of gum should be retained by the tobacco in order to give luster or gloss to its surface as well as strength and elasticity to its texture. Besides this, the tobacco when resweated should not 30 continue to ferment longer than is deemed necessary while it is under the process, because when the operator determines the fermentation to have been sufficient his judgment is based upon results already apparent 35 to him, and additional fermentation not only deprives the tobacco of more gum than should be taken from it, but also changes its color from that which it was intended to have, and these after effects not infrequently render the tobacco 40 unfit for the use to which it would otherwise have been put, and consequently its value is depreciated.

After experimenting for some time I have discovered a practical method of treating tobacco whereby I am enabled to control the sweat or fermentation, and to settle and retain so much of the gum as it is desired the tobacco shall possess, as well as to insure the required shades of color and to improve the 45 texture.

My method of treatment consists in first subjecting the tobacco to the influence of heat until fermentation is induced and kept up for a sufficient time, and there arresting the fermentation by subjecting the tobacco to the influence of a refrigerating agent, and keeping it under such influence until the fermentation has ceased and the gum becomes settled, and, if need be, in repeating the alternate influences 50 of heat and refrigeration until the desired results are obtained.

In practice I may carry my process of treatment into effect by any suitable mechanical means, making use of suitable heating appliances by means of which fermentation may be reduced, and of any refrigerating agent adapt-

ed to have the desired action or effect upon the tobacco.

In the drawing I have shown as one means of applying the refrigerating agent a series of 70 pipes, N O P Q, located in a room in which tobacco may be stored, such pipes being intended to have connections with a refrigerating-machine made to cause a circulation of ammonia-gas, cold brine, or other refrigerating agent, through the pipes in the room. Such a means would probably be too expensive for the treatment of small quantities of tobacco; but it would be well adapted for use in the treatment of large quantities kept in 80 storage in a warehouse or store-room.

For the treatment of small quantities of tobacco I prefer to construct a room in the form of a small ice-house, leaving sufficient space in the center for the tobacco which is to be put 85 under treatment, and in this connection to use ice as the refrigerating agent.

For the purpose of heating the tobacco, in order to induce fermentation or sweat, a room similar to that shown in the drawing but having pipes therein which are connected with a heating apparatus, may be used, as well as may any ordinary sweat-room. If the rooms in which the tobacco is stored are not sufficiently warm to sweat the tobacco, it is taken 95 and sweated in an artificially-heated room to the precise extent required, when the fermentation is arrested by subjecting the tobacco to the influence of the refrigerating agent until the gum becomes settled and the fermentation 100 ceases, or, if desired, until the tobacco is required for use.

Where the tobacco has been marketed with no more care than has heretofore been exercised respecting its treatment, or if it has received no special treatment, my method of treatment may commence with arresting natural fermentation, if there be any, or I may continue the aging of the tobacco, under the effects of refrigeration, until such time as it is 105 put into the resweating process. As soon as the tobacco has been sufficiently resweated or fermented to eliminate, if need be, its rank elements or produce the desired shades of color, I take it from the process of resweating and subject it to the influence of the refrigerating agent until the gum becomes settled and fermentation ceases, and, if necessary, until such time as the tobacco is required for use. Sometimes, however, I commence my course of treatment by 110 refrigeration after the tobacco has been put into the resweating process and is sufficiently resweated in which case the fermentation is arrested and the flow of the gum stayed in the manner before stated.

I find that the alternate action of heat and refrigeration are beneficial when they can be controlled and carried to such an extent simply as may be requisite to obtain the ultimate results to be reached. It sometimes happens, 115 however, that the tobacco is of such a nature as to require unusual care in its treatment, and

I find that beneficial results may in some instances be obtained by regulating the degrees of temperature which the refrigerating agent is made to produce in the room for containing the tobacco to be subjected to its influence—
 5 as, for instance, if the tobacco is under particular degrees of temperature in the resweating process, it may be advisable to reverse the treatment by so regulating the refrigerating agent as to secure temperatures which produce directly opposite effects upon the tobacco. Again, it may be desirable to determine beforehand the temperature at which the refrigerating agent is to act, and, having the atmosphere of the room into which the tobacco is to be put at the particular temperature decided upon, the tobacco under fermentation may be taken and subjected to refrigeration at the predetermined temperature. In other instances
 10 it may be necessary or advisable to vary the temperature of the refrigerating-room during the course of treatment. The different conditions under which the tobacco is subjected to the influence of the refrigerating agent are,
 15 however, variations of detail, which, like those of the resweating process, are to a certain extent dependent upon the requirements of the tobacco under treatment, as determined by the judgment of the operator.
 20 From the experiments which I have made I have demonstrated to my entire satisfaction the beneficial results attained by the treatment of tobacco by subjecting it alternately to the influence of heat and a refrigerating agent,
 25 and I regard such treatment as being very important, inasmuch as the constant and uncontrolled draining of the gum from the tobacco, which has heretofore taken place, is injurious to the texture and changes the shades of color.
 30 Not only so, such draining is liable to, and in many instances does, continue until the fiber

becomes dry and brittle and assumes a dead appearance, which, even though the tobacco be moistened to permit of its manipulation, will soon reappear; and if the tobacco has been 45 manufactured into cigars the sale of such cigars injures the reputation of the manufacturer, because smokers, as a rule, desire fresh glossy cigars, and no cigars can be kept fresh for more than a short time unless the tobacco 50 possesses the requisite amount of gum and has sufficient strength of texture to enable them to withstand the atmospheric influences to which they are subjected when put on sale.

I do not here claim, broadly, the process of 55 treating tobacco by subjecting it to the influence of a refrigerating agent, the same being the subject of another application of which this is a division; but

What I do claim, and desire to secure by 60 Letters Patent, is—

1. The improvement in the art of treating tobacco, whereby its texture is improved and the desired colors are obtained, which consists in subjecting it alternately to the influences 65 of heat and refrigeration, substantially as described.

2. The improvement in the art of treating tobacco under sweat or fermentation, which consists in arresting fermentation by subjecting the tobacco to the influence of a refrigerating agent, then again inducing fermentation by subjecting it to the action of heat, then arresting fermentation, as before, and keeping the tobacco under the influences of heat and 70 refrigeration until the desired results are produced and fermentation ceases, substantially as described.

GEORGE STORM.
